CHARLES E. STEWART, OF SAN FRANCISCO, CALIFORNIA.

BOAT-HANDLING APPARATUS.

1,068,183.

Specification of Letters Patent.

Patented July 22, 1913.

Application filed June 3, 1912. Serial No. 701,197.

To all whom it may concern:

Be it known that I, CHARLES E. STEWART, a citizen of the United States, residing in the city and county of San Francisco and

5 State of California, have invented new and useful Improvements in Boat-Handling Apparatus, of which the following is a specification.

This invention relates to apparatus for 10 hoisting and lowering, swinging and releasing boats, and particularly relates to an apparatus for handling life boats of the type usually carried by passenger and other vessels.

15 The object of the present invention is to provide an apparatus whereby a life boat may be suspended or connected to davits, with mechanism whereby the device may be simultaneously operated to swing a boat 20 from inboard position to outboard position; to provide means for holding the davits in their respective positions; and to provide in such an apparatus means whereby the life boat may be readily disconnected from 25 the davits at the desired time.

It is a further object of the present invention to provide an improved life boat apparatus, having especially in view the 30 purpose of more effectually, rapidly and safely handling the life boat until it is finally resting upon the water.

Another object of the invention is to 35 evolve a life boat handling apparatus of such design, arrangement and combination as will eliminate to the greatest possible extent the number of hands required, and to provide an apparatus which will automatically lock itself during the handling 40 of the life boat in the event of the injury or loss of presence of mind of one of the operators, thereby preventing the too rapid lowering of the life boat when in the outboard position.

45 It is a further object of the present invention to provide a life boat handling apparatus and device for quickly and simultaneously releasing the life boat from its supporting davits as the exigency may require.

50 The invention consists in the provision of an apparatus whereby a life boat may be turned from an inboard position, when it is so arranged, to an outboard position by a positive movement under the control of one man; means being provided for raising and lowering the life boat with a uniform speed

at each end so as to maintain the boat on an even keel, and consisting of a device in the life boat whereby it is released from the supporting davits when necessary.

60 It also comprises details of construction which will be more fully explained by reference to the accompanying drawings, in which—

Figure 1 is a plan view of the apparatus 65 shown as arranged with a life boat in inboard position. Fig. 2 is a side elevation of the apparatus with a life boat swung to outboard position and also into proximity with the water. Fig. 3 is a detail view 70 of the automatic winch lock and controlling brake and davit actuating worm. Fig. 4 is a detail perspective view of a trip-latch forming a part of the boat releasing mechanism.

75 Referring to Fig. 1, there is illustrated a life boat 2, which may be of any suitable type and size, and which is braced in the inboard position and connected to davits 3 and 4 of an appropriate type, having vertical spindles 5 turnable and supported in suitable bearings 6 secured to the sides of the ship 7. The life boat 2 is shown as being provided with eye-bolts 8 substantially secured adjacent to its ends; the upper end of each of the eye-bolts being provided with a link 9, to the upper end of which is pivoted a trip-pawl or lever 10, Fig. 4, over which is slipped the eye 11 of a sheave block 12. Through the sheave block 90 12 is rove a tackle rope 13, one end of which is connected to the upper sheave block 14 through which the rope is rove, and thence continued to a guide pulley 15 on a davit, as 3; the tackle or hoisting rope 95 thence continuing to and winding upon a flange drum 16 mounted in suitable bearings 17 on the deck of the ship 7. Obviously the releasing device 9—10 at each end of the ship is connected by means of respective blocks 12 to the respective davits 3—4. In order to release the life boat from the blocks 12, when desired, there is slidably upon the link 9 and the trip-lever 10 a tie or slip link 18 provided with eyes 19, 100 through one of which slides the link 9, and through the other the arm or lever 10; the slip link 18 being connected by a chain, cable or other appropriate connection 20 which runs over guide pulleys 21 fastened 110 in the life boat 2, and over which the release chain 20 runs longitudinally toward

and around suitable guide pulleys 22, thence upwardly and being connected to a handle or ring 23 which may be located at a convenient position in the life boat 2. When a 5 person desires to release the life boat from the supporting tackle, a pull on the handle or ring 23 draws on the cable or chain 20 and this in turn pulls the slip links 18 along the trip-arm 10 and the load of the 10 boat causes the arm 10 to swing about its adjacent end of the link 9 and slip through the rings 11 of the supporting blocks 12, thereby clearing the life boat from the supporting tackle.

15 For the purpose of raising or lowering the life boat 2 with a uniform speed and in a positive manner so as to obviate entirely the requirement of several hands operating on the ropes 13, these ropes are connected, as 20 before stated, to respective winding drums 16, each of which is secured upon a common shaft 25 turnable in the bearings 17. When the shaft 25 is revolved in one direction or 25 the other, it will wind or unwind the ropes 13, as the case may be, uniformly throughout its movement. The shaft 25 may be revolved to wind the drums through an appropriate mechanism, here shown as comprising a gear 26 which may be fastened to one 30 of the drums 16. Meshing with the gear 26 is a pinion 27, secured on a spindle 28, which also carries a gear 29 meshing with a pinion 30, which is secured on a jack-shaft 31 on which is secured at each end a crank 32. 35 The cranks 32 may be manually or power driven, as desired, to drive the mechanism and wind the ropes simultaneously and at uniform speed on their respective drums 16 which are connected by the common shaft 25.

40 Assuming that it is desired to lower a life boat by the present apparatus, a single operator may control the lowering operation by releasing the drum shaft 25 with the drums 16 from the control of a locking lever 45 33 which is pivoted or otherwise mounted, as at 34, upon a substantial support and which has an arm 35 engageable with a ratchet or other suitable wheel, as 36, fast to a winding drum. When the operator actuates the locking lever 33 to carry its arm 35 from restraining engagement with its cooperative locking device, as the ratchet wheel 36, then the drums will be released and the boat lowered by the uniform unwinding of 50 the suspended tackle ropes 13. If for any reason the operator should become injured or incapacitated, the locking lever 33 will automatically become operative by the reaction of a spring 37, which is effective on 55 the lever 33 to throw it into locking engagement with the winch structure the instant that the pressure of the operator's hand is removed from the lever 33.

In order to control the speed of the lowering of the boat 2 as its ropes 13 unwind

from the drum 16, a suitable brake device 7c may be employed, and this is in the present instance indicated as consisting of a drum 38 which may be secured to the spindle 28. The drum is embraced by a strap or band 39, one end of which is fast and the other end of which is connected to a handle or lever-arm 40. The lever-arm 40 may be pivoted, as at 41, so that a pull on the lever 40 will bind the strap 39 upon the brake drum 38 and the friction thereof will effectually check the rotation of the drums 16. 75

It will be seen that one operator can control the drum-locking lever 33 to unlock the drums and the same operator can control the brake lever 40 so that he may govern the speed of the lowering of the life boat 2. By the provision of the automatic locking device 33 should the operator be disabled, the device will automatically become operative 80 to lock the winding drum until another operator could be substituted for the one disabled or incapacitated.

85 An important feature of the present apparatus is the means whereby the davits 3 and 4 may be positively and simultaneously 90 swung to carry the boat from an inboard position to an outboard position. This control of the davits is accomplished by one man through means of a gear 42 fast on one 95 of the davits, as 3, and which is engaged by a worm 43, secured on a shaft 44 which is mounted in appropriate bearings 45; the shaft 44 being provided with a crank 46. When the boat is stored inboard and connected to the davits 3 and 4, if it be desired 100 to swing it outboard, an operator manipulating the crank 46 will, through means of the worm 43, turn the davit 3 and this, being connected to its adjacent end of the life 105 boat, will swing its end of the life boat and simultaneously through the connection of the boat shift the other davit 4. As the davit 3 is continued in its swinging movement from an inboard position to an outboard position by the rotation of the worm 43 and the davit gear 42, and as the davit 3 reaches its outermost position, the davit 4, through means of the connecting boat 2, will be drawn outwardly until the boat 2 110 assumes a position parallel, substantially, with the vertical side of the ship. If desired a man may be stationed at the opposite end of the boat 2 from the operator of the crank 46 to watch out for the boat until 115 it is finally properly positioned.

120 From the foregoing it will be seen that the present invention consists of a pair of davits connected to and by a life boat; means being provided for positively operating the davits, said means being operable by a single man. After the operator has 125 swung the davits through the actuation of the davit-controlling device the davits will be locked in their outboard or other posi- 130

tions at all times by means of the worm 43 and the gear 42 which also, as stated, forms the means for swinging the davits. Having actuated the davits through the worm gear 42—43 until the boat is positioned outboard, the same operator may then move that one of the winding drums 16 which is provided with the control mechanism including the levers 33 and 40, and by properly actuating the former the drums will be released to lower away the life boat; the speed of the lowering being controlled by the brake 38—39 with its lever 40. As before stated in the emergency of the operator becoming incapacitated for any reason, the life boat will be prevented from falling violently to the water by the automatic action of the lock lever 33 which may be released again as soon as properly operated.

Assuming that the life boat 2 has been the last to lower away from the ship and one man remains on board to control the lowering away device, as soon as the boat is in juxtaposition to the surface of the water the one man can slide down one of the suspending ropes 13 and land safely in the life boat, and thereupon the latter can be instantly released from the suspending ropes 13 by a pull on the release handle or ring 23, which will operate to pull the cables 20, and the sliding or slip link 18 will be drawn from restraining engagement with the swinging arm 10 at each end of the life boat and disconnected from the blocks 12.

By the provision of the clips connected immediately to the boat, in the event that a sea strikes the boat as it approaches the

water and lifts it bodily, relieving the boat from the tackle, then the clips will automatically release this from the tackle and the boat will be free. Should a sea strike one end of the boat causing it to pitch, the seaman in charge may pull the clip-releasing device so that the boat would be released entirely from the supporting tackle.

Having thus described my invention, what I claim and desire to secure by Letters Patent is—

In a boat handling apparatus, davits and their tackle for supporting a boat, a shaft extending from davit to davit, winding drums at the ends of the shaft to which the rope of the tackle is attached for simultaneous winding or unwinding, one of the drums having a gear and a stop wheel, a windlass having a crank-shaft and gearing operated thereby for turning the gear, a brake drum and a manually operated brake controlling the operation of the power gear, an automatically operating safety lever engageable with the stop wheel, said windlass having a crank-shaft independent of the winding crank-shaft and carrying a worm, and a worm wheel on the adjacent davit whereby the davit may be revolved to swing the boat from one horizontal position to another at the deck.

In testimony whereof I have hereunto set my hand in the presence of two subscribing witnesses.

CHARLES E. STEWART.
